UNITED STATES PATENT OFFICE.

FREDERICK VAN DUZER LONGACRE, OF YONKERS, NEW YORK, ASSIGNOR TO INGER-SOLL-RAND COMPANY, OF JERSEY CITY, NEW JERSEY, A CORPORATION OF NEW JERSEY.

CLEARANCE UNLOADER.

Application filed October 19, 1925. Serial No. 63,308.

The invention relates to compressors, but more particularly to clearance unloaders, and the primary object of the invention is to obtain clearance control for a compressor 5 by means and devices which avoid using available valve space.

To accomplish this object one or more clearance chambers are located intermediate the cylinder and the discharge connection, 10 and certain of the main discharge valves between the clearance chambers and the cylinder are adapted to perform the additional 15 function of clearance control valves. Auxiliary discharge valves may be provided between the clearance chamber and the discharge connection, so that when the main discharge valves are rendered inoperative for freely opening the clearance chamber to unload the cylinder, the auxiliary valves 20 function as discharge valves.

Further objects of the invention will hereinafter appear and the invention is illustrated in the accompanying drawing, which is a diagrammatic longitudinal sectional elevation of so much of a compressor as will 25 serve to make the invention clear.

Referring to the drawing, the compressor cylinder A is provided with the reciprocating piston B and the usual water jacket 30 C. In this instance the compressor is shown as double acting, having the inlet D and the discharge connection E adapted to be connected to a suitable receiver, not shown. Any suitable or usual inlet valves F, shown 35 in this instance of the plate type, are provided for each end of the cylinder, and there may be as many of these valves as necessary or desirable.

Clearance chambers G and H are located 40 in the cylinder casing intermediate the cylinder A and the discharge connection E, and suitable discharge valves J and K, shown in this instance of the plate type, are located in the valve openings L and O between the clearance chambers G and H and each end 45 of the cylinder A. Auxiliary discharge valves P and Q are provided in the valve openings R and S between the clearance chambers G and H and the discharge connection E. Additional discharge valves, if 50 desired, may be provided for each end of the cylinder controlling communication between the cylinder and the discharge connection E, but, for simplicity of illustration, these 55 additional discharge valves are not shown.

Suitable means are provided for rendering the main discharge valves J and K inoperative for unloading the compressor in one or more steps by reducing the cylinder capacity, and in this instance the valve J is 60 provided with pressure fluid means for lifting the entire valve structure from its seat T in the cylinder while the valve K is shown with a hand-operated means for lifting the valve from its seat U in the cylinder, and 65 either one of these devices may be used, as desired.

A yoke V is connected to the valve J and a piston W in the cylinder X is connected by the rod Y to the yoke V, so that outward movement of the piston W in the cylinder X lifts the entire valve structure J 70 from its seat and renders the valve inoperative, so that the volume of the clearance chamber G is added to that of one end of 75 the cylinder A for reducing the capacity of the cylinder.

The auxiliary discharge valve P operating in conjunction with the main discharge valve J may also be provided with similar 80 controlling means, comprising the piston Z in the cylinder a connected by the rod b to the yoke c, which in turn is connected to the valve structure P. Suitable pressure fluid connections for the cylinders X and a 85 are provided in the form of pipes d and e, which may be controlled manually or automatically, as desired, and the connections are such that when pressure fluid is supplied to the pipes d the piston W of the valve J 90 will be actuated inwardly to maintain the valve on its seat so that it functions as a main discharge valve, while the piston Z of the auxiliary valve P is actuated outwardly to remove the valve P from its seat, 95 and permit free passage of fluid under pressure from the clearance chamber G to the discharge connection E. By opening the pipe connection d to atmosphere and applying pressure fluid to the pipe connection e, 100 the relative movement of the pistons W and Z is reversed and the main discharge valve J is lifted from its seat and rendered inoperative while the auxiliary valve P is returned to its seat and becomes 105 operative to function as a discharge valve. In such case the compressor cylinder is unloaded to the extent of the volume of the clearance chamber G. A plurality of such clearance chambers G may be 110

provided for the same end of the cylinder, as desired, and controlled in the same manner by the main discharge valves.

Hand-operated means are shown in connection with the main discharge valve K for lifting the valve from its seat, in this instance the yoke f being connected by a screw threaded stem g to the hand or wheel h. The stem g co-operates with an internally screw threaded portion j of the cap or cover k, so that rotation of the stem g raises and lowers the valve structure K. The auxiliary valve Q is preferably secured in fixed position in the valve opening S in any suitable manner and does not require mechanism for raising and lowering same, because if desired the auxiliary valves P and Q may remain operative at all times.

I claim:

- 20 1. In a compressor, the combination of a cylinder and piston, an inlet valve, a discharge connection, a clearance chamber, a main discharge valve for discharging the compressed fluid through said clearance chamber to the discharge connection, means for rendering said main discharge valve inoperative, whereby free communication is afforded between the cylinder and clearance chamber for unloading the compressor by reducing the cylinder capacity, and an auxiliary discharge valve between the clearance chamber and the said discharge connection.
- 25 2. In a compressor, the combination of a cylinder and piston, an inlet valve, a discharge connection, a clearance chamber intermediate the cylinder and said discharge connection, a main discharge valve between the cylinder and said clearance chamber, an auxiliary discharge valve between the clearance chamber and the discharge connection, and means for rendering the main discharge valve inoperative for unloading the compressor by reducing the cylinder capacity.
- 30 3. In a compressor, the combination of a cylinder and piston, an inlet valve, a discharge connection, a clearance chamber intermediate the cylinder and said discharge connection, a main discharge valve between the cylinder and said clearance chamber, an auxiliary discharge valve between the clearance chamber and the discharge connection, and means for rendering the main discharge valve inoperative for unloading the compressor by reducing the cylinder capacity.
- 35 4. In a compressor, the combination of a cylinder and piston, an inlet valve, a discharge connection, a clearance chamber intermediate the cylinder and said discharge connection, a main discharge valve between the cylinder and said clearance chamber, an auxiliary discharge valve between the clearance chamber and the discharge connection, and means for automatically rendering the main discharge valve inoperative while permitting the auxiliary discharge valve to function normally, thereby unloading the compressor by reducing the cylinder capacity.
- 40 5. In a compressor, the combination of a cylinder and piston, an inlet valve, a discharge connection, a clearance chamber intermediate the cylinder and said discharge connection, a main discharge valve between the cylinder and said clearance chamber, an auxiliary discharge valve between the clearance chamber and the discharge connection, and means for maintaining either one of said valves operative while the other is held inoperative for loading and unloading the compressor.
- 45 6. In a compressor, the combination of a cylinder and piston, an inlet valve, a discharge connection, a clearance chamber, main and auxiliary discharge valve structures including plate valves for discharging the compressed fluid through said clearance chamber to the discharge connection, means for bodily lifting the said main discharge valve structure from its seat in the cylinder to render the main discharge valve inoperative while maintaining the auxiliary discharge valve structure upon its seat, whereby free communication is afforded between the cylinder and clearance chamber for unloading the compressor by reducing the cylinder capacity, and means for also lifting the auxiliary discharge valve structure from its seat in the clearance chamber to completely unload the cylinder.

intermediate the cylinder and said discharge connection, a main discharge valve between the cylinder and said clearance chamber, an auxiliary discharge valve between the clearance chamber and the discharge connection, and pressure fluid means for automatically rendering the main discharge valve inoperative while permitting the auxiliary discharge valve to function normally, thereby unloading the compressor by reducing the cylinder capacity.

4. In a compressor, the combination of a cylinder and piston, an inlet valve, a discharge connection, a clearance chamber intermediate the cylinder and said discharge connection, a main discharge valve between the cylinder and said clearance chamber, an auxiliary discharge valve between the clearance chamber and the discharge connection, and means for maintaining either one of said valves operative while the other is held inoperative for loading and unloading the compressor.

5. In a compressor, the combination of a cylinder and piston, an inlet valve, a discharge connection, a clearance chamber, main and auxiliary discharge valve structures including plate valves for discharging the compressed fluid through said clearance chamber to the discharge connection, means for bodily lifting the said main discharge valve structure from its seat in the cylinder to render the main discharge valve inoperative while maintaining the auxiliary discharge valve structure upon its seat, whereby free communication is afforded between the cylinder and clearance chamber for unloading the compressor by reducing the cylinder capacity, and means for also lifting the auxiliary discharge valve structure from its seat in the clearance chamber to completely unload the cylinder.

In testimony whereof I have signed this specification.

FREDERICK van DUZER LONGACRE.
